[57] **CLAIM**

The ornamental design for a socket assembly for an
electric lamp fixture, as shown and described.

DESCRIPTION

FIG. 1 is a front elevational view of the socket assembly
for an electric lamp fixture showing my new design;
FIG. 2 is a rear elevational view thereof;
FIG. 3 is a left side elevational view thereof;
FIG. 4 is a right side elevational view thereof;
FIG. 5 is a top plan view thereof on a reduced scale;
FIG. 6 is a bottom plan view thereof on a reduced scale;
and,
FIG. 7 is a perspective view thereof on a reduced scale.
